Primary Examiner — Lauren D McVey

CLAIM

The ornamental design for a letter stamp case, as shown and described.

DESCRIPTION

FIG. 1 is a front perspective view of a letter stamp case, showing my new design;

FIG. 2 is a front view thereof;

FIG. 3 is a rear view thereof;

FIG. 4 is a right side view thereof;

FIG. 5 is a left side view thereof;

FIG. 6 is a bottom view thereof;

FIG. 7 is a top view thereof; and,

FIG. 8 is a front perspective view thereof in a disassembled state.

The broken lines immediately adjacent to the claim depict the bounds of the claimed design, while all other broken lines are directed to environment. The broken lines form no part of the claimed design.

1 Claim, 8 Drawing Sheets
